(57) **CLAIM**

The ornamental design for a regulator for a heating installation, as shown and described.

DESCRIPTION

Cross reference is made to copending U.S. design patent application Ser. No. 29/644,014 entitled "Regulator for a Heating Installation" by Fritz et al., which was filed on Apr. 13, 2018.

FIG. 1 is a perspective view of a regulator for a heating installation showing our new design;

FIG. 2 is a front elevational view of the regulator for a heating installation of FIG. 1;

FIG. 3 is a rear elevational view of the regulator for a heating installation of FIG. 1;

FIG. 4 is a left side elevational view of the regulator for a heating installation of FIG. 1;

FIG. 5 is a right side elevational view of the regulator for a heating installation of FIG. 1;

FIG. 6 is a top plan view of the regulator for a heating installation of FIG. 1; and,

FIG. 7 is a bottom plan view of the regulator for a heating installation of FIG. 1.

The broken lines shown in the drawings illustrate portions of the regulator for a heating installation that form no part of the claimed design.
